UNITED STATES PATENT OFFICE.

JOHN W. ALLISON AND WILLIAM H. BAUER, OF SYLVIA, KANSAS.

SELF-MEASURING FAUCET.

SPECIFICATION forming part of Letters Patent No. 653,835, dated July 17, 1900.

Application filed April 19, 1900. Serial No. 13,535. (No model.)

To all whom it may concern:

Be it known that we, JOHN W. ALLISON and WILLIAM H. BAUER, citizens of the United States, residing at Sylvia, in the county of Reno and State of Kansas, have invented certain new and useful Improvements in Self-Measuring Faucets; and we do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in faucets, and especially to a self-measuring faucet, which may also be utilized as an ordinary faucet without using the measuring part of the device.

More specifically, the invention consists in the provision of a stationary spigot member which is apertured and of a turning plug which is held in contact with a flattened portion of the spigot, the adjacent faces of said flattened portions having ducts which when turned into certain positions will allow the liquid to flow through registering passage-ways either from the spigot into a measuring-receptacle and thence through an outlet passage-way after a slight rotary movement is given to the plug or turned into other positions in which the liquid is allowed to pass directly from the spigot to the outlet passage-way without passing into the measuring-receptacle.

To these ends and to such others as the invention may pertain the same consists, further, in the novel construction, arrangement, and combination of parts, as will be herein-after more fully described and then specifically defined in the appended claim.

Our invention is clearly illustrated in the accompanying drawings, which, with the letters of reference marked thereon, form a part of this application, and in which—

Figure 1 is a perspective view of our improved spigot. Fig. 2 is a vertical longitudinal sectional view through the spigot and turning plug. Fig. 3 is a detail in perspective of the turning plug. Fig. 4 is a perspective view of the spigot with turning plug removed.

Reference now being had to the details of the drawings by letter, A designates the spigot, longitudinally apertured, and the outer end 55 of said spigot is flattened, as at A', and said flattened portion is centrally apertured, as at a, and a duct A² leads through same and communicates with the longitudinal bore or aperture in the spigot A. An outlet passage-way 60 B leads through the projecting portion B' of the spigot, and merging into said outlet passage-way is a second duct C. These ducts are preferably spaced apart, as shown in the drawings.

The turning plug D has a flattened face D', which is centrally apertured, as at d, and a duct D² passes through said head. A curved segment-groove E is formed in said flattened face D' and is disposed near the outer margin 70 of the plug. In adjusting the plug to the flattened portion of the spigot a bolt F is passed through an aperture d in the latter and passed through the registering aperture a in the center of the flattened portion of the 75 spigot, and the lower end of said bolt, which is threaded, carries an adjusting-nut G, between which nut and the under face of the spigot is disposed a spring H, whereby the plug may be held against the flattened portion 80 of the spigot and the frictional contact of the two flat faces regulated by increasing or diminishing the tension of said spring.

On the edge of the flattened portion of the spigot are secured the two angled stop-pins 85 K and L, which when turned with their free ends upward will be disposed in the path of the recessed rim M of the turning plug, and as one or the other of the shouldered portions D³ and D⁴ comes in contact with said pins the 90 rotary movement of the plug is limited.

When the spigot is used in connection with the measuring-receptacle, the pin L is turned down and the plug may be turned to the left until the shoulder D⁴ contacts with the upturned pin K, in which position the duct D² 95 will be in registration with the duct A², allowing liquid to pass from the spigot into the measuring-receptacle R, which is mounted upon and has screw-threaded connection with the plug D. When the plug is turned in the opposite direction until the shoulder D³ contacts with the pin K, the duct D² will register with the duct B and allow the contents of the

measuring-receptacle to pass out through the exit passage-way C.

When it is desired to utilize the faucet without reference to the measuring-receptacle or graduate, the plug is turned so that one end of the segment-groove E will come opposite the end of the duct A², while the opposite end of said segment will come into a position over the duct C, which communicates with the outlet passage-way B. In this adjustment of the plug with reference to the faucet the pin K is turned down and the pin L turned up to form a stop. As the plug is turned so that the shoulder D³ will contact with the pin L the end of the segment-groove will be in registration with the duct A², allowing the liquid to pass through the duct A², groove E, and duct C to the outlet passage-way. As the plug is thrown to its limit in the opposite direction the shoulder D⁴ will come in contact with the pin L and the flow of the liquid will be cut off.

The pins K and L are frictionally held in apertures in the spigot, and in order to hold same in upright positions to form stops pins N may be placed in apertures in the spigot on either side of said pins K and L, as shown.

From the foregoing it will be noted that the device may be equally well utilized as a measuring or as an ordinary faucet, the parts may be easily and quickly taken apart when it is desired to cleanse the faucet, and the tension of the spring may be regulated so that the two contact-faces of the spigot and plug may be held against leakage.

We are aware that it is common in the art

to construct measuring-faucets in which, by a partial rotation of a plug, ducts may be brought into registration, so that liquid may pass from the spigot into a measuring or graduate receptacle, while by a partial rotary movement of the plug other ducts are brought into registration to allow the liquid to pass from the receptacle to and through the outlet passage-way. Hence we do not claim such a construction broadly.

Having thus described our invention, what we claim to be new, and desire to secure by Letters Patent, is—

A measuring-faucet comprising the stationary portion having a flattened end, and ducts extending through same and opening through the face of said flattened portion, a turning plug having a flattened portion, and duct leading through same, a curved recess in the flattened face of said plug, a central aperture formed through the plug and spigot, a threaded bolt passed through said central apertures which are in registration, a nut on said bolt, a spring interposed between said nut and the under face of the spigot, and the stops for limiting the rotary movement of the turning plug, as set forth.

In testimony whereof we affix our signatures in presence of two witnesses.

JOHN W. ALLISON.
WILLIAM H. BAUER.
